David Davis

UNITED STATES PATENT OFFICE.

CHARLES W. BECK, OF ROCKVILLE CENTER, NEW YORK, ASSIGNOR, BY MESNE ASSIGNMENTS, TO THE BECK-FROST CORPORATION, OF DETROIT, MICHIGAN, A CORPORATION OF MICHIGAN.

TOOL-CLAMP.

1,143,025.

Specification of Letters Patent. Patented June 15, 1915.

Application filed August 3, 1910. Serial No. 575,263.

To all whom it may concern:

Be it known that I, CHARLES W. BECK, a citizen of the United States, and resident of Rockville Center, county of Nassau, and State of New York, have invented certain new and useful Improvements in Tool-Clamps, of which the following is a specification.

The object of this invention is to provide a simple device by means of which a plurality of tools may be securely held together to form a compact and convenient package for storing in a tool box.

Another object of the invention is to provide a simple device of the class described by means of which a series of wrenches, or similar tools, may be secured in a compact package convenient for storage in automobile tool boxes, and to so construct the device that the tools may be practically instantaneously released from the clamp, and removed therefrom.

In the drawings, Figure 1 is a side elevation of the device showing a series of wrenches held therein; Fig. 2 an end view of the device with the clamp released; Fig. 3 an end view thereof showing the clamp in its locked position; Fig. 4 a plan view, the locking device being in the position shown in Fig. 2; Fig. 5 a side elevation of a slightly different form of the device; Fig. 6 a front elevation of the device shown in Fig. 5; and Fig. 7 a side elevation with the clamping device released.

Referring to the various parts by numerals, 1 designates a series of wrenches secured within the clamping device. The clamping device consists of a holding frame 2 bent to form the rectangular holding socket 3 having the long side arm 4, and the opposite short side arm 5, said arms being connected by the wall 6. At the outer end of the short arm 5 an offset 7 is formed, and at the outer end of said offset portion is an outwardly extending cam arm 8, said arm being bent outwardly to form the cam 9. The cam arm is apertured for the passage for the clamping bar 10, and the long arm 4 of the socket is correspondingly apertured to receive the end of the clamping bar. This arm is also formed with the radial slots 11 which extend outwardly from the margin of the aperture; and the clamp bar is provided at its

end with radial pins 12 which are adapted to be passed through the slots 11, and serve to hold the clamp bar in position when said bar is partially rotated to carry said pins out of register with said slots. The outer end of the clamp bar is provided with a cross pin or bar 13 which serves the double purpose of means for rotating the bar, and as means for binding on the cam 9, and thereby drawing the two arms of the clamp together.

In operation the series of wrenches or other tools are placed side by side in the rectangular socket 3, as illustrated in Fig. 1, and the inner end of the clamp rod is passed through the aperture in the long arm 4 of the socket. This brings one end of the cross pin 13 against the cam wall 8, and by a partial rotation of the said rod said pin will ride on the cam 9 and draw the two arms of the clamp toward each other, thereby securely clamping the wrenches or other tools within the rectangular socket 3. It will thus be seen that by a slight turn of the clamping bar the wrenches may be either locked in the socket to form a convenient package for storing in an automobile tool box, or they may be released from the socket, depending on the direction of rotation of the locking bar.

In Figs. 5, 6 and 7 is illustrated a slight variation in the form of the means for drawing together the arms of the clamp. In these views the locking bar is provided at its inner end with a threaded portion 14 which is adapted to enter a correspondingly threaded aperture in the long arm 4^a of the clamp. The locking bar 10^a is provided with a head 15 which is adapted to bear against the portion 8^a of the clamp, whereby when the rod is screwed into the arm 4^a the said head 15 will draw the two arms of the clamp together.

By providing the offset portion 7 the locking pins 12 or the threaded portion 14 may be withdrawn from the path of the tools so that they may be freely removed from the socket. This offset portion also insures the clamping of the tools within the socket 3 as it stiffens one side of the clamp about midway the ends thereof, thus insuring the inward movement of the arm 5 under the influence of the clamping bar.

From the foregoing it is manifest that I provide a very simple and easily operated clamp in which the tools may be very quickly locked, or from which they may be almost instantly released.

Having thus fully described my invention, what I claim as new and desire to secure by Letters Patent is:

1. A tool clamp comprising a holding frame formed with a socket and provided with side arms, one of said arms being offset at the outer end of the socket and both of said arms being apertured beyond the socket, an exterior cam formed on one of the arms adjacent the perforation, a clamp rod extending through the perforations in the arms and provided with means adapted to interlock with both of said arms and to engage said cam to draw the two arms together.

2. A tool clamp comprising a holding frame bent to form a rectangular socket to receive a series of tools, the side arms of the frame extending beyond said socket and one of the arms being offset near the outer end of the socket, and both of said arms being apertured, an exterior cam formed on one of said arms, the opposite arm being provided with radial slots extending outwardly from the aperture therein, a clamp rod adapted to be passed through the apertures and provided with interlocking pins at its end adapted to pass through the said radial slots, and a cam engaging part secured to the other end of the clamp rod and

adapted to engage the exterior cam to draw the two arms together.

3. A tool clamp comprising a holding frame formed with a socket and provided with side arms extending outwardly beyond the socket, one of said arms being laterally offset at the outer or open end of the socket, both of said arms being apertured beyond the offset portion of one of said side arms, a clamp rod extending through the perforations in the arms and provided with means adapted to engage both of said arms to draw them toward each other, the end of said clamp rod being adapted to lie in the laterally offset portion of one of the side arms, when said rod is disconnected from said arms and the socket is opened.

4. A tool holder comprising a holding frame having two arms forming a socket, a clamping rod extending across between said side arms and connecting them together, means at both ends of said clamping rod to engage the side arms and a cam surface formed on one of the side arms and adapted to be engaged by the clamping rod, whereupon the rotation of the clamping rod the side arms of the holding frame will be drawn toward each other.

In testimony whereof I hereunto affix my signature in the presence of two witnesses this 1st day of August 1910.

CHARLES W. BECK.
